YARN GUIDE FOR WINDING MACHINE
Richard L. Walden, Warwick, R.I., assignor to Leesona Corporation, Warwick, R.I., a corporation of Massachusetts

Filed Sept. 8, 1964, Ser. No. 394,836
8 Claims. (Cl. 242—18)

The present invention relates to yarn guides for textile winding machines and is concerned more specifically with a yarn guide adapted to temporarily engage a moving strand of yarn and, after passage of a predetermined interval, to release the strand. It may, for example, find application to a winding machine having a constantly traversing means and a package which must achieve normal rotating speed from rest position, the yarn guide of the invention directing the yarn to the package until normal speed has been reached and then releasing the yarn to the traversing means.

In U.S. Patent 2,764,362 to Goodhue et al. entitled "Winding Machine," issued September 25, 1956 there is disclosed and claimed a fully automatic winding machine for winding yarn, or the like, into various forms of packages, especially cones. In essence, the machine of this patent consists of a winding section including a winding mandrel mounted for controlled movement between a winding position, a braking position, and a reverse rotation position and a driving drum for the winding mandrel which is provided with an endless groove to traverse the yarn being wound upon the mandrel; an end-finding and re-uniting section, operable in the event of thread breakage, including a knitter and separate means for finding the respective free ends of the broken yarn and for conveying them to the knitter to be joined together; a preliminary yarn servicing section including means for detecting, tensioning and cleaning the yarn supplied to the mandrel; and an enclosed control section for superintending the various other sections and controlling the functioning thereof. In the arrangement of the patent, the yarn knitter was supported on a part of the machine frame at a site slightly forwardly and adajacent to one end of the winding mandrel and the driving drum therefor.

As already indicated, upon thread breakage during the winding operation, the machine was equipped with means for locating both of the free ends of the broken yarn and for delivering these ends to the knitter, which, after re-uniting the ends, released the yarn to the traversing groove of the driving drum, whereby winding could proceed as before. During the end-finding sequence and incidentally thereto, the winding mandrel was rotated first to braking position to halt its forward rotation and then to reverse rotation position at which the mandrel was rotated backwardly to allow the delivery end of the broken thread to be extricated from the wound convolutions of the package on the mandrel, engaged by a suitably designed device and delivered to the knitter. When the yarn ends were re-united by the knitter, the winding mandrel was moved to braking position to halt reverse rotation and then to winding position to reinitiate normal advance of the thread onto the package. All the while these several operations were being performed, the rotation of the grooved driving roll proceeded at full speed with the result that when the thread was released by the knitter, it was immediately engaged by the groove of the roll and traversed back and forth onto the package at the same rate as for normal winding. However, the timing of the release of the yarn from the knitter coincided substantially with the movement of the winding mandrel to normal winding position, at which stage the winding mandrel had essentially zero speed of rotation and an appreciable interval necessarily had to pass before the mandrel had accelerated to normal operating speed

2

by virtue of frictional contact with the peripheral surface of the driving drum.

During this interval, the yarn was being traversed at the regular rate but was being advanced, at least in the beginning, at a much reduced rate. Consequently, instead of being wound in the usual convolutions upon the package, the yarn was merely zig-zagged in the closely spaced loops, i.e., laid in a compressed sinuous pattern, on the package periphery with the period of the loops growing longer and longer until the package had finally achieved normal take-up speed to lay down the convolutions in the normal pattern. The existence on the package of such zig-zagged loops was found to be quite objectionable when the yarn was processed subsequently, as during weaving, rewinding, etc., since they naturally tended to introduce unexpected slack as well as to sluff off the package and form snarls or become entangled in parts of the machine.

There are several ways in which a solution to this problem could be approached. For example, the rotation of the driving drum could be checked during the end-finding cycle and then restarted in timed relation to the return of the winding mandrel to the winding position, or the yarn knitter could be designed so as to retain the yarn temporarily and deliver the same to the traverse roll only when the package was up to speed. However, it will be rather obvious that either of these approaches would require rather complex mechanism carefully integrated with the yarn end-finding cycle and add measurably to the complexity of an already highly complicated machine.

A further solution is set forth in U.S. Patent 3,055,602, to Carlton A. Steele, entitled "Yarn Guide With Delayed Yarn Release for Winding Machines," issued September 25, 1962. In this patent, there is disclosed and claimed a supplementary yarn guide member interposed between the knitter and the traverse roll for receiving the united strand from the knitter and holding it out of its normal path and in spaced relationship to the traversing roll a predetermined period to permit the winding package to attain winding speed whereafter the yarn is released to said traversing roll. The supplementary yarn guide as disclosed in the patent just cited takes the form of a grooved tubular member and the interval for which the yarn is delayed between the time it is released from the knitter and deposited into the traverse roll is determined by three conditions: The speed of travel of the yarn, the lead angle of the helical groove, and the effective length of the supplementary yarn guide. While the supplementary yarn guide of the U.S. patent just cited has proved highly effective in use, it has been found that when a rather large mass of yarn is wound on the winding mandrel and the mandrel is subsequently moved through the end-finding sequence already described the package may not have attained its normal operating speed, due to the greater inertia of this larger package, before the yarn is released from the supplementary yarn guide to said roll. In such event the yarn may zig-zag in the undesirable pattern already alluded to hereinbefore.

It is, therefore, an object of the present invention to provide a simple device which is adapted to receive the yarn from the knitter after reunion of the broken ends thereof and temporarily supplant the grooved driving roll as the guiding means for the yarn until the package has regained normal speed of rotation.

Another object of the present invention is a delayed action yarn guide mechanism upon which the yarn is deposited by the knitter of an automatic winding machine, said guide being adapted to retain the yarn thereon until the passage of a suitable interval of time to allow the package being wound to achieve normal speed of rotation and then discharge the yarn onto the periphery of the

traverse roll for delivery to the normally rotating package.

A further object of the invention is to provide an elongated tubular guide having a helical groove on the periphery thereof and supported at one end from the frame of the winding machine for free rotation with respect thereto, the lead angle of said groove being inclined forwardly and outwardly toward the supported end, the axis of rotation of the tubular member extending in spaced parallel relationship to the axis of the traverse roll of the machine to maintain the path of the yarn passing over the guide out of the endless groove of the traverse roll, the opposite end of the tubular member terminating within the longitudinal confines of the traverse roll, whereby yarn deposited on the roller between its ends will engage the peripheral helical groove and cause the tubular member to rotate as the yarn advances, rotation of the member resulting in the yarn being displaced axially of the member away from the supported end, and means for receiving the yarn after its initial passage along said tubular member to redeposit the yarn on said tubular member adjacent the supported end of said member once again to cause the yarn to advance over the tubular guide a second time, the yarn finally dropping off the opposite end of the traverse roll.

These and other objects and advantages will appear from the following detailed description when read in conjunction with the accompanying drawing in which:

FIG. 1 is a view in front elevation of the improved yarn guide means of the present invention in operative association with a winding mandrel, a grooved package driving and yarn traverse roll, and a yarn knotted of a winding machine, parts of the present invention being shown in their operative, loaded positions; and

FIG. 2 is a right end view of the arrangement of FIG. 1; and

FIG. 3 is a fragmentary view similar to FIG. 1 but illustrating parts of the invention in their inoperative, unloaded positions; and

FIG. 4 is a view similar to FIG. 3 but illustrating parts of the invention in the position assumed as loading of the mechanism is completed and prior to retraction of the loading arm; and

FIG. 5 is an exploded view of the mechanism of the instant invention.

Before beginning the detailed description of the guide of the invention, attention should perhaps be directed to the fact that while the guide was particularly designed for use in association with the winding machine of U.S. Patent 2,764,362 and, for purposes of illustration, is shown in connection with the related components of such a machine, it is adapted to be employed with other types of winding machines as well and will, in fact, find application with any system for winding yarn which includes a constantly moving yarn traverse member, whether in the form of a groove roller or otherwise, and a winding mandrel which at some time during the winding operation must achieve winding speed from essentially a rest condition.

Turning now to a detailed description of the invention, there is shown in the drawings only enough of the related structure of the machine of U.S. Patent 2,764,362 as is necessary to an understanding of the application of the present invention thereto. Thus, numeral 10 designates the delivery package being wound upon a conical yarn holder 12 supported on a winding mandrel 14. Mandrel 14 is mounted for rotation upon a shaft 16 which is connected to the remainder of the winding section machine (not shown) in such a way as to permit the package to grow in size as the yarn Y is wound thereon. In the drawings, the machine is set up for the winding of a conical package or cop but it will be appreciated that other shapes and types of factors could be wound as well by replacing the conical mandrel and yarn holder with other mandrels and holders appropriate to the formation of the particular package desired.

Package 10, holder 12, and mandrel 14 are adapted to be rotated by frictional contact of the package surface with the periphery of an elongated cylindrical driving drum or roll 18 disposed upon a shaft 20 for rotation therewith. As already indicated, shaft 20 is subject to constant rotation, the means by which the shaft is driven being omitted here. Drum 18 is provided on its periphery with an endless groove 22 which is adapted to engage the yarn being delivered to package 10 and traverse that yarn back and forth lengthwise of the package, the axis of the drum being disposed, for that reason, generally at right angles to the path of the yarn to package 10.

Rearwardly of drum 18, i.e., to the right in FIG. 2, there is provided a rest plate 19 onto which the package is moved, by means not shown, in order to bring the package to rest when yarn flow is interrupted. Eventually, when yarn continuity is re-established, the package is returned to contact with driving drum 18 to be brought again to winding speed thereby. Additional movement can be imparted to the package intermediate the two stages just mentioned, as is explained in U.S. Patent 2,764,362, but such movement has no bearing on the present subject matter, and is not described here.

Located adjacent the left end (FIG. 1) of package 10 and drum 18 is a vertically arranged bracket 24 forming a part of the rigid frame for the winding machine, only the upper end of that bracket being visible in the drawings. Attached to this end of bracket 24 is a yarn knotted 26 comprising a box-like housing containing the operative mechanism of the knotted and an arcuate bill 28 projecting from the side of housing 26 proximate to the package and driving roll. The major portion of the vertical dimension of housing 26 lies above the axis of drum 18, and bill 28 projects from a point adjacent the upper end of the housing downwardly and endwardly generally in the direction of the midpoint of drum 18 but terminates somewhat above the level of the uppermost point of the drum periphery. The details of the knotted 26 form no part of the present invention but may be, and preferably are, substantially the same as those disclosed and claimed in U.S. Patent 2,670,230 to Goodhue. For purposes of clarity of understanding of the present invention, however, it will serve to point out that knotted 26 includes a vertically oriented rack-bar 30 which is slidable in a vertical path in response to rotation of a tooth pinion 32 fixed on a rotatable shaft 34. The lower end of rack-bar 30 is provided with an angular arm 38 which extends into the plane of traverse roll 18 and lays substantially parallel with the axis of said traverse roll. The outer end of arm 38 has a pin 40 embedded therein and extending inwardly toward traverse roll 18. Thus far, the description has been confined essentially to the parts of the winding machine disclosed and claimed in U.S. Patent 2,764,362, which, in themselves, have no essential relation to the present invention except to establish a context for the description thereof.

In accordance with the present invention a generally V-shaped support member 44 is fixed at its inner edge, i.e., its lefthand edge as viewed in FIG. 1, to frame bracket 24. The upper opposite ends of support member 44 are directed inwardly to form opposed bearing surfaces one of which is shown at 46, to receive the opposite ends of an elongated tubular member 50 and support said tubular member for free rotation therebetween. Tubular member 50 may be, and preferably is, substantially the same as that disclosed and claimed in U.S. Patent 3,055,602 and reference should be had to that patent for further details of the construction and operation of tubular member 50. It will suffice here to note that tubular member 50 has a helically grooved periphery 52, the purpose of which is to receive the re-united strand of yarn which has been joined at knotted 26 and delivered thereto via bill 28. The strand of yarn finds its way into a portion of groove 52 and causes member 50 to rotate by virtue of

frictional engagement of the strand with the groove side-walls, such rotation, due to the inclination of the groove, gradually advancing the strand along the length of member 50, from left to right as viewed in FIG. 1, until it passes off the outer end thereof and descends onto the periphery of drum 18 to be engaged by groove 22 and traversed onto package 10.

Support member 44 is provided with an appendage 56 which has a post 58 embedded therein. A rather irregularly shaped plate or "yarn carrier" 60 is mounted on post 58 for rocking movement thereabout and is retained on said post by a clamp ring 62. A torsion spring 64 surrounds post 58 and has one end hooked about a wall of appendage 56 with the opposite end of the spring connected to yarn carrier 60. Spring 64 acts to bias yarn carrier 60 about post 58 in a counterclockwise direction as viewed in FIGS. 1, 3 and 4.

The movement of yarn carrier 60 in a clockwise direction (FIGS. 1, 3 and 4) is controlled by upward movement of pin 40 which engages with a foot 66 folded inwardly from the lower end of said yarn carrier. As fully explained in the earlier cited U.S. Patent 2,764,362, as knotter 26 is prepared for its knot-tying operation, rack-bar 30 is elevated by pinion 32. This motion causes arm 38 to travel upwardly carrying pin 40 into contact with foot 66 and causing yarn carrier 60 to rock in a clockwise sense about post 58.

To the end that yarn carrier 60 may be yieldably held in its operative or loaded position to operate in a fashion to displace the yarn from the outer end of member 50, i.e., from the end remote from knotter 26, to the inner section thereon, i.e., the section proximate to knotter 26, there is provided a latch or trigger 70 which includes a U-shaped bearing section 72 at one of its ends having suitable holes pierced therethrough to loosely receive a stud 74 about which the trigger is rockable. Stud 74 is affixed to member 44. A clamp ring 75 snaps on the outer end of stud 74 to hold trigger 70 on the stud. The opposite end of trigger 70 is upturned and terminates in a yarn engaging bail 76 which normally lays in the horizontal plane of and closely adjacent to member 50. The medial portion of trigger 70 is bent to a generally horizontal section which provides a detent 78 for engaging a shoulder 80 formed in one side of yarn carrier 60. The lower edge of trigger 70 adjacent bearing section 72 is folded downward and outward as an ear 82 which is engageable with a camming pin 84 protruding inwardly from the interior side of yarn carrier 60. In a manner to be further described hereafter, pin 84 is operable to rock trigger 70 clockwise as yarn carrier 60 rocks counterclockwise (FIGS. 1, 3 and 4). A rather light spring 86 is supported on stud 74 with one of its ends bearing against bearing section 72 of trigger 70 and the opposite end of the spring wrapped about a pin 88 protruding from the side of member 44. Spring 86 serves to bias trigger 70 in a counterclockwise direction about stud 74 (FIGS. 1, 2 and 4). The limit of such counterclockwise movement of trigger 70 under the influence of spring 86 is controlled as the edge 90 of said trigger strikes against pin 88. In this position bail 76 is essentially parallel with member 50 and disposed in the horizontal plane thereof, see FIGS. 1 and 4. Obviously, spring 86 can be selected to afford any desired force within reasonable limits to urge trigger 70 against pin 88. However, as will be more fully explained hereafter, it is necessary that the tension in the winding yarn overcome the force of said spring 86 in order to release yarn carrier 60 from engaging with trigger 70. Thus, spring 86, in the usual case, is selected so as to provide adequate biasing force to hold detent 78 in engagement with shoulder 80, yet to be yieldable under somewhat less than the average operating tension in yarn being wound so as to effect release of yarn carrier 60 from trigger 70.

When yarn carrier 60 and trigger 70 are interlocked by

virtue of engagement of shoulder 80 with detent 78 the upper surface 92 of said carrier is situated in the horizontal plane of tubular member 50, said surface 92 being disposed between bail 76 and member 50. Moreover, surface 92 is slightly inclined from left to right (FIGS. 1, 2 and 4) in order that the yarn travelling along member 50 can engage readily on said surface. As seen in FIGS. 1 and 4, the upper edge of bail 76 is slightly elevated over surface 92 in the horizontal plane thereby causing the yarn being advanced along tubular member 50 and along surface 92 to travel eventually onto bail 76 and thereby depress trigger 70 to release yarn carrier 60 for counterclockwise movement.

Upon release of yarn carrier 60 from trigger 70, the strand of yarn engaged in the groove 52 of tubular member 50 is lifted upwardly and redeposited in the groove 52 of said member at the end adjacent knotter 26. A yarn engaging finger 94 is arranged at the upper end of yarn carrier 60, said finger projecting upwardly above surface 92 in order to engage the yarn in cooperation with said surface 92 to carry the yarn to the inner end of tubular member 50. Finger 94 is rockably supported on a shank 96 which has a hole therethrough to loosely receive a rivet 98 connecting it with yarn carrier 60. A light torsion spring 100 is attached at one end to a tab 102 folded inwardly from shank 96. The opposing end of spring 100 is bent inwardly through a small aperture in the side of yarn carrier 60 so that said spring 100 is operative to bias finger 94 and its companion shank 96 counterclockwise (FIGS. 1, 3 and 4) on rivet 98. An ear 104 is bent outwardly from shank 96 to engage the upper end of yarn carrier 60 to limit the counterclockwise movement of shank 96. In order that the yarn may be released from finger 94 to slide off surface 92 after the yarn has been delivered to the inner end of tubular member 50, the finger is cammed downward below the plane of surface 92. For this purpose a pin 106 is fixed in the side of member 44, said pin laying in the rotary path of travel of tab 102. As shank 96 is moved due to counterclockwise movement of carrier 60 tab 102 abuts against pin 106. Consequently, shank 96 is rocked clockwise (FIGS. 1, 3 and 4) on rivet 98 to depress finger 94 below the margin of surface 92. Pin 106 is also operative to arrest counterclockwise movement of yarn carrier 60. Thus, a pin 108 is fastened in the side of yarn carrier 60 and protrudes inwardly, laying in the plane of tab 102. As said tab 102 bears against pin 106, said pin 108 engages against the opposite side of the tab to prevent further movement past said pin 106 by the yarn carrier.

To the end that the yarn Y may be guided onto surface 92 and over bail 76 a guide bar 110 is affixed to bracket 24 and extends laterally therefrom parallel to tubular member 50. The upper edge of guide bar 110 is situated generally in the plane of surface 92, but is located somewhat forwardly of yarn carrier 60, as best seen in FIG. 2.

It is believed that the operation of the foregoing mechanism will be quite apparent from the preceding description. However, a summary of the operation will now be presented.

In the manner fully set forth in U.S. Patent 2,764,362 an interrupted strand of yarn is re-united at knotter 26 whereafter the yarn is released for descending, sliding movement over bail 28. Tubular member 50 intercepts the yarn Y and provides the function of guiding the yarn outwardly, axially of said member 50, at a predetermined rate to eventually discharge the yarn Y off the outer end thereof onto traverse drum 28 all as fully set forth in U.S. Patent 3,055,602. As has already been stated, as a first incident of preparing the knotter for uniting the ends of the yarn strand pinion 32 is rotated to raise rack-bar 30. In consequence thereof arm 38 is elevated causing pin 40 to rise and abut against foot 66. Further elevating movement of arm 38 causes yarn carrier 60 to rock clockwise around post 58. Simultaneously therewith, trigger 70 is relieved of the pressure of pin 84 against ear 82, where-

upon spring 86 rocks said trigger counterclockwise about stud 74. As surface 92 and bail 76 arrive at substantially horizontal positions shoulder 80 slides over detent 78, the detent snapping upward by spring 86 to yieldably secure yarn carrier 60 and trigger 70 together, as shown in FIG. 4. By virtue of the clockwise motion of yarn carrier 60 as just described tab 102 is released from contact with pin 106 whereby spring elevates ear 94 to a position raised above surface 92. Arm 38 thereupon descends away from foot 66. Thus, the mechanism is set in its operative, cocked position as illustrated in FIG. 1.

With the mechanism so arranged the yarn ends are united at knotter 26 and the yarn laid in groove 52 of tubular member 50 in the fashion already mentioned. Consequently the yarn Y travels through groove 52 at a predetermined rate, eventually engaging on surface 92. During this initial travel of said yarn along tubular member 50 it is delivered over guide-bar 110 to insure that the yarn will be guided into engagement with surface 92, such placement of the yarn Y being achieved as the yarn is delivered to the knotter by the yarn delivery means therefore fully described in the earlier cited Goodhue et al. patent.

Since the yarn Y continues in groove 52 as it engages surface 92, the yarn slides along said surface and eventually rides up on bail 76. At this time the yarn Y, which is under tension, depresses bail 76 releasing detent 78 from shoulder 80 and, in effect, firing the trigger 70. Consequently, yarn carrier 60 snaps counterclockwise under the influence of spring 64. The yarn strand becomes caught at the intersection of surface 92 and ear 94 and is delivered to the inner end of tubular member 50 adjacent knotter 26 to be deposited in groove 52 thereof whereupon the yarn Y commences a further pass axially of said tubular member. Ear 94 is cammed out of engagement with the yarn Y as tab 102 engages pin 106. Moreover, trigger 70 is rocked clockwise on stud 74 to clear the path for the yarn during its second pass along tubular member 50, as illustrated in FIG. 3. The mechanism thus remains in this inoperative position until arm 38 is once again elevated as part of a yarn re-uniting cycle. By virtue of the fact that guide-bar 110 is slightly shorter than the intersecting point of ear 94 and surface 92, the yarn Y is directed under said guide-bar on its second pass along tubular member 50.

It has already been stated that an additional passage of the yarn Y over tubular member 50 as contemplated by the instant invention is advantageous in gaining additional time during which package 10 can be accelerated to its winding speed. The weight of such packages is, of course, a paramount consideration in the time-speed relationship. In lighter packages of yarn it may occur that one pass of the yarn along the tubular member 50 will afford all the time that is required to accelerate the package. In this event the tension in the winding strand of yarn Y will have increased to a value desired to wind the package with suitable density characteristics. By selecting spring 100 to exert a sufficiently light force which can be overcome by the full winding tension the present invention is operable, under appropriate conditions, to provide but a single pass of the yarn over tubular member 50. Thus, once again reverting to the instant when trigger 70 is fired to release yarn carrier 70, as already described, ear 94 is swung into abrupt engagement with the yarn strand. However, since it is now assumed that the package has accelerated to its normal operating speed and, therefore, the tension in the yarn has attained its normal winding value and, further, since spring 100 is overcome by this tension, ear 94 is depressed by the yarn and yarn carrier 60 rocks counterclockwise disengaged from the yarn. The yarn simply continues its outward movement in groove 52 and is discharged into groove 22 of drum 20 after but a single pass over tubular member 50.

From what has been said it will be appreciated that the

present invention provides a simple and inexpensive solution to the problem of avoiding undesirable formation of zig-zag loops on the wound package during the end-finding cycle of an automatic winding machine, even in the presence of heavy yarn packages requiring greater time to overcome the proportionally greater inertia, and accelerate to winding speed.

What is claimed is:

1. In a machine for winding a strand of yarn onto a rotating package and including traverse means for directing said strand onto said package, wherein said package is brought from rest condition up to speed while said traverse means is moving, the improvement therein comprising; an elongated member having a yarn receiving section adapted to receive said strand for delivery to said traverse means, a yarn discharge end for releasing said strand to said traverse means, and means for advancing said strand from the receiving section to the discharge end; sensing means for engaging said strand during its initial advance toward said discharge end; and a yarn carrier operable in response to engagement of said yarn with said sensing means to redeposit said strand on said receiving section whereby to induce further advance of said strand from said receiving section to said discharge end of said member.

2. Apparatus as set forth in claim 1 wherein said sensing means includes a detent for engaging and holding said carrier in an inactive position, said detent being released in response to engagement of said yarn with said sensing means to free said carrier for operation to redeposit said strand on said receiving section.

3. Apparatus as set forth in claim 2 wherein said yarn carrier includes a finger for engaging said strand, and a surface for guiding said strand to said finger; and cam means for releasing said finger from said strand when the strand is redeposited on said receiving section.

4. Apparatus as set forth in claim 3 including resilient means for biasing said finger to an operative position to engage said strand, said finger being movable to an inoperative position to release said strand therefrom when the tension in the strand exceeds a predetermined value whereby said strand continues its initial advance toward said discharge end.

5. On an automatic winding machine for winding a strand of yarn onto a rotatably driven package of the type wherein said package is brought to rest in the event of an interruption in said strand during the winding operation and is brought up to winding speed when continuity of the strand is re-established, said machine including traversing means for traversing the winding strand longitudinally of the package, a knot-tying device spaced from the normal path of the strand during winding to unite the strand after an interruption in said strand and yarn guide means associated with said knot-tying device and terminating above the normal strand path; the combination therewith of a supplementary yarn guide interposed between said yarn guide means and said traversing means for receiving said united strand from said yarn guide means to hold said strand out of its normal path in spaced relationship to said traversing means, said supplementary yarn guide being adapted to move said strand from a yarn receiving section thereof to a yarn discharge end thereof for release to said traversing means, both said yarn receiving section and said discharge end being located within the longitudinal confines of said traversing means, said supplementary yarn guide having a portion intermediate said yarn receiving section and said discharge end to retard the advance of the strand along said supplementary yarn guide and retain the strand on the supplementary yarn guide for a predetermined period of time, sensing means for engaging said strand during its initial advance toward said discharge end, and a yarn carrier operable in response to engagement of said yarn by said sensing means to re-

deposit said strand on said receiving section whereby to induce further advance of said strand from said receiving section to said discharge end of said supplementary yarn guide.

6. Apparatus as set forth in claim 5 wherein said sensing means includes a detent for engaging and holding said carrier in an inactive position, said detent being released in response to engagement of the yarn with said sensing means to free said carrier for operation to redeposit said strand on said receiving section.

7. Apparatus as set forth in claim 6 wherein said yarn carrier includes a finger for engaging said strand, and a surface for guiding said strand to said finger; and cam

10

means for releasing said finger from said strand when the strand is redeposited on said receiving section.

8. Apparatus as set forth in claim 7 including resilient means for biasing said finger to an operative position to engage said strand, said finger being movable to an inoperative position to release said strand therefrom when the tension in the strand exceeds a predetermined value whereby said strand continues its initial advance toward said discharge end.
